MACHINE FOR COVERING HEELS

Lewis J. Bazzani, Swampscott, Mass., assignor to
United Shoe Machinery Corporation, Paterson,
N. J., a corporation of New Jersey

Application December 30, 1935, Serial No. 56,739

41 Claims. (Cl. 12—49.1)

This invention relates to the manufacture of shoes and is illustrated as embodied in a machine for covering heels.

In covering wood heels of the Louis type it is customary adhesively to secure a single piece of sheet material commonly known as a cover to the rear and side faces of the unattached heel and then to secure the forward, the top and the bottom projecting margins of the cover upon the margins of the breast, the attaching and the top-lift receiving faces respectively of the heel. After the partially covered heel has been attached to the shoe, the breast of the same is covered by a flap which is split from the heel end of the sole 15 of the shoe and is adhesively secured to the heel breast.

Heel covering machines of various types have been proposed. It is an object of this invention to provide an improved machine for applying covers to the rear and side faces of heels of various shapes quicker and more effectively than has heretofore been possible. In accordance with one feature of the present invention the illustrated machine comprises a holder for a heel, a resilient pad for supporting a cover, and means comprising the pad constructed and arranged to apply the cover to the rear face of the heel progressively from one end of the heel to the other, and cooperating means for then applying the cover progressively to the sides of the heel. In the illustrated construction the pad is supported by a pair of plates which are spaced by an opening, the central part of the pad having a depending portion which fits within the opening. The heel holder is mounted for movement about an axis to swing the heel against the cover and into the pad, the cover being applied to the rear face of the heel progressively from the attaching end to the tread end of the heel as the heel with the pad wrapped about it is moved into the opening between the pad-supporting plates. The plates are mounted for movement about parallel axes respectively which are disposed at approximately right angles to the axis of rotation of the heel holder. After the cover has been applied to the rear face of the heel, the pad-supporting plates are swung about their respective axes to wrap the cover and the pad about the sides of the heel, the supports being rotated until the projecting margins of the cover have been applied to the respective margins of the attaching, the breast and the top-lift receiving faces of the heel. One type of pad illustrated is provided with a pocket which is filled with sand composed of round particles thereby insuring that the pad may be readily de-

formed to a considerable extent under pressure of the heel. By effecting relative swinging movement of the heel and the pad while applying the cover to the heel, the cover is progressively forced against the heel by a tensioned, relatively hard convex surface of the pad. As the convex surface of the pad applies the cover to the heel, it moves along the same in the form of a traveling wave and stretches the cover as it applies the same to the heel, thereby insuring that the cover shall be free from wrinkles. The unlaid portion of the cover is slightly tensioned before it is applied to the heel through the provision of clamps which force the lateral margins of the cover against the pad throughout the covering operation and which are moved under pressure of the pad.

The output of the machine is increased by mounting a plurality of units, each of which comprises one of the cover-applying pads and a pair of pad-supporting plates, upon a turret. Suitable mechanism is also provided for holding the pad in wrapped relation with the heel while the turret is being indexed from an operating station to a discharge station thereby permitting the cover-attaching cement to dry while the cover is forced against the heel. The turret is indexed in timed relation with the cover-applying mechanism of the machine, the operator, after placing the heel in the holder, having only to trip a treadle to set the machine in operation for the purpose of covering the heel and indexing the machine. The above machine covers heels of various shapes quickly and effectively and materially reduces the cost of the heel-covering operation.

These and other features of the invention, including certain details of construction and combinations of parts, will be described as embodied in an illustrative machine and pointed out in the appended claims.

In the drawings,

Fig. 1 is a side elevation, partly broken away, of the illustrated machine;

Fig. 2 is a front elevation of the machine;

Fig. 3 is a plan view of the machine, a portion of which has been broken away and a pad of which has been removed;

Fig. 4 is an enlarged side elevation, partly in section, showing the positions of the operative parts of the machine after the cover has been applied to the heel;

Fig. 5 is a perspective view showing one of the units of the turret of the machine positioned at an operating station of the machine;

Figs. 6 to 10, inclusive, are perspective views illustrating five different stages of the heel-covering operation;

Fig. 11 is a plan view of one of the units of the 5 turret after the heel has been covered;

Fig. 12 is a sectional view taken along line XII—XII of Fig. 11;

Fig. 13 is a perspective view of a modified pad;

Fig. 14 is a perspective view of a heel after it 10 has been covered by the use of the above machine; and

Fig. 15 is a perspective view of the heel shown in Fig. 14 after the projecting margins of the cover have been trimmed flush with the heel.

15 The illustrated machine is described with reference to applying a celluloid cover to the rear and side faces of a Louis heel 22. During the heel-covering operation, the top, the front and the bottom projecting margins 24, 26 and 28, 20 respectively (Fig. 14), of the heel are inturned upon and secured to the attaching, the breast, and the top-lift receiving faces of the heel 22. After the upstanding portions of the margins of 25 the cover 20 have been trimmed flush with the heel (Fig. 15) and the heel has been attached to a shoe (not shown) the breast of the heel is covered by a flap (not shown) which is split from the grain side of the rear end of the sole of the shoe. Although the machine is illustrated 30 with reference to applying celluloid covers 20 to heels 22 it will be understood that the machine may be used for applying covers of various kinds of material to heels or to work pieces of various shapes.

35 Preparatory to applying the celluloid cover to the heel, the cover is softened by inserting the same in a bath of a suitable solvent, the edge portions of the heel being previously coated with cement. Before a leather or fabric cover is applied to the heel it is customary to coat the cut-side face of the heel as well as the inside face of the cover with cement or other suitable adhesive.

40 The heel to be covered is carried by a heel holder 30 which is mounted for swinging movement about a bearing 32 supported by a bracket 34 which is secured to the main frame 36 of the machine by screws 35 through mechanism which will later be described. The cover to be applied to the heel is placed upon a pad 38 mounted upon 45 supports or plates 40 which are spaced to form an opening 42 (Fig. 3). The pad 38 comprises a central depending portion 44 which is positioned within the opening 42 between the supports 40. The heel 22 which is securely gripped by the holder 30 is forced against the cover 20 and into the central portion of the pad 38 thereby applying the cover to the rear face of the heel 50 progressively from the attaching face of the heel (Figs. 6 and 7) to the top-lift receiving or tread face of the heel.

55 After the cover has been applied to the rear face of the heel the supports 40, which are provided with trunnions 46 swiveled upon a turret 60 48, are swung upwardly to wrap the lateral margins of the pad 38 about the sides of the heel, thereby applying the cover 20 progressively to opposite sides of the heel. The supports 40 may be swung upwardly to the vertical positions illustrated in Figs. 4 and 12 in order to insure that the pad 38 shall apply the top, the front, and the bottom projecting margins 24, 26 and 28 of the cover to the attaching, the breast, and the top-lift receiving faces, respectively, of the heel.

75 After the cover 20 has been applied to the heel

22 the upstanding margins of the celluloid cover 20 (Fig. 14) are trimmed flush with the heel (Fig. 15).

In order to insure that the cover-attaching cement shall dry before pressure of the pad 5 against the covered heel is relieved the turret 48 is provided with six cover-wrapping units which are successively moved to and past the covering station 50, the turret being intermittently actuated by suitable indexing mechanism which is 10 operated in timed relation with the heel-covering mechanism and will be described later.

Power to operate the machine is supplied through a drive shaft 52 (Fig. 1). A worm 54 which is keyed to the drive shaft 52 is in meshing engagement with a gear 56 secured to a cam shaft 58 rotatably mounted in the frame of the machine. A bevel-gear 60 is keyed to the cam shaft 58 and meshes with a bevel-gear 62 pinned to the lower end of a shaft 64 which is rotatably supported by the main frame. A crank 66 (Fig. 3) is keyed to the upper end of the shaft 64 and carries a roll 68 constructed and arranged successively to engage within slots 70 formed in a cam plate 72 which is positioned beneath the turret 48 and is secured to the turret. An arcuate portion 74 of the crank 66 is in engagement with one of a plurality of concave surfaces 76 of the plate when one of the covering units of the turret is positioned at the operating station 50, 30 the arrangement being such that after the turret has been indexed, it is held against rotation during the time the cover 20 is being applied to the heel 22 at the covering station 50. The turret 48 and the cam plate 72 are rotatably mounted 35 upon a cylindrical extension 78 (Fig. 4) of a bearing 80 which supports the turret and the cam plate 72 and which is secured by screws 82 to the main frame.

The bracket 34 upon which the heel holder 30 40 and the operating mechanism therefor is mounted is secured to the top of the cylindrical extension 78 by screws 35 as above stated. In order to support the front end of the turret 48 against downward displacement during the heel-covering operation, the bottom face of the turret is continuously in engagement with a brace 86 (Fig. 4) secured by screws 88 to a circular plate 90 which is fastened to the machine frame by screws 92.

50 The heel holder 30 comprises a rear abutment 94 provided with a plurality of sharp teeth 96 for engaging the central portion of the attaching face of the heel, and a front abutment 98 constructed and arranged to engage the tread and 55 the breast faces of the heel. The front abutment 98 is adjustably secured through a slot-and-screw connection 100 with relation to an abutment carrier 102 mounted upon a bearing rod 104. The abutment carrier 102 may be adjustably secured through the provision of a slot-and-screw connection 106 to an arm 108 which is pivotally mounted upon the bearing rod 104. The arm 108 is swung in a clockwise direction, as viewed in Fig. 1, by a roll 110 which is mounted upon a 60 rocker arm 112, during a portion of the cycle of operation of the machine, thereby swinging the front abutment 98 away from the rear abutment 94, the arm 108 at all times being held in contact with the roll 110 through the provision of 65 a spring 114. The lower part of the spring 114 is positioned within a cavity formed in a lever 116 and the upper part of the spring fits within a cavity of the arm 108. The effective strength of the spring 114 may be varied by turning a 70 75

screw 118 which is in threaded engagement with the arm 108 and engages a washer 120 which is inserted in the cavity and engages the upper end of the spring. A grip plate 122 is secured to the lever 116 by screws 124 and is positioned in front of the rear abutment 94.

When the machine is started by stepping upon a treadle 125 which trips a one-revolution clutch 126, the roll 118 of the rocker arm 112 is raised thereby permitting the spring 114 to cause the front abutment 98 to swing toward the rear abutment 94, the attaching face of the heel being forced with considerable pressure against the teeth 96 of the rear abutment as the grip plate 122 is flexed. In order to position the heel in the holder 30 the operator forces the attaching face of the heel against the flexible grip plate 122 and moves the tread and breast faces of the heel into engagement with the abutment 94. The heel is centralized in the holder by sight and has its lip forced into engagement with a gage 123 which is adjustably secured to the grip plate 122. When the operator releases his hold on the heel the grip plate 122 forces the heel against the front abutment 98 with sufficient pressure to retain the heel in position until the abutment 98 forces the attaching face of the heel against the teeth 96 of the rear abutment 94. Heels of different pitches may be accommodated in the machine by adjusting the abutment 98 with relation to the abutment carrier 102, and heels of different heights may be accommodated in the machine by adjusting the abutment carrier 102 with relation to the arm 108.

35 The rocker arm 112 is mounted upon a bearing 128 secured to the bracket 34 and is pivotally connected to a rod 130 the lower end of which is pivotally connected to a bell-crank lever 132 mounted upon a bearing 134 supported by the 40 machine frame. The lower end of the bell-crank lever 132 carries a follower roll 136 which engages within a groove 140 of a cam 142 keyed to the shaft 58.

The depending portion 44 of each of the pads 38 45 engages a base pad 144 (Figs. 10 and 12) of soft rubber, which is mounted upon the turret 48 beneath the opening 42 formed between the plates 49 and fills a recess 146 formed in the upper surface of the turret 48. In order to improve the 50 effective operation of the pad 38 when operating upon heels having sharp curvatures, the pad is provided with a pocket 148 which is filled with sand 149 consisting of round particles which shift readily under pressure during the heel-covering operation. The sand is inserted in the pocket 148 through a tube 151 (Fig. 10) which is in threaded relation with a cap 153.

As the heel holder 30 is swung toward the pad, the upper end of the rear face of the heel engages the cover positioned upon the pad (Fig. 6) and upon continued movement (Fig. 7) of the holder 30, the rear face of the heel is swung against the cover and into the pad thereby causing the cover to be applied to the rear face of the heel progressively from the attaching face to the top-lift receiving face of the heel. As the rear face of the heel is swung against the cover and into the pad 38 the portion 150 (Fig. 7) of the pad which is located immediately in advance of the portion of the pad applying the cover to the heel, assumes a convex shape, as viewed from the side of the heel. The convex portion 150 of the pad is tensioned and travels progressively ahead of the portion of the cover 70 which is being applied to the heel as the holder

30 continues its downward swinging movement. It will be noted that throughout the covering operation the lateral portions of the cover are forced against the pad 38 by a pair of clamps 152. The clamps 152 are yieldingly movable 5 under pressure of the pad and will later be described in detail.

The pad may be made entirely of rubber as will later be described. It has been found preferable, however, to provide the pad with the pocket 148 10 which is filled with the round particles of sand 149 in order to insure that when full Louis heels are being covered, convex cover-applying surfaces of sharp curvatures shall be formed on the pad. The sand 149 offers a substantial amount 15 of resistance to displacement and provides a firm backing for the cover-supporting surface of the pad 38. As the heel in the holder 30 swings downwardly against the cover and into the pad 38 the convex portion 150 of the pad moves toward 20 the tread end of the heel and rolls the cover against the rear face of the heel as it travels along the same. The cover may therefore be described as being applied to the heel by the traveling wave action of the pad 38. The pad 38 is 25 freely movable under pressure with relation to the supports 40, thereby permitting the pad to creep relatively to the heel as it is compressed between the heel and the supports. The pad 38 therefore stretches the cover as it applies the 30 same to the heel. The bearing 32 about which the holder 30 is rotated is so arranged that the heel being covered has a rearward component of movement while it forces the heel against the cover and into the pad. 35

After the cover has been applied to the rear face of the heel, the pad supports 40 are swung upon the trunnions 46 to cause the pad to wrap the cover 29 about the sides of the heel. The holder 30 in the meanwhile continues to force the heel into the central portion of the pad 38 and into the opening 42. As above stated, the supports 40 are usually swung into the upright positions best illustrated in Fig. 12 in order to apply the projecting margins 24, 26 and 28 of the cover to 45 the attaching, the breast, and the top-lift receiving faces of the heel. The mechanism for operating the supports 40 will be described later.

The opening 42 formed between the spaced supports 40 is enlarged at its rear end in order to accommodate the wide upper portion of the heel. As shown in Fig. 8, when the machine is idle the axes 154 about which the supports 40 are swung are spaced from and positioned above corresponding inner ends or end faces 156 of the supports 40, the arrangement being such that as the supports 40 swing to the vertical positions, the opposing end faces 156 of the respective supports 40 move away from each other, thereby increasing the width of the opening 42 in order 60 to insure that the resistance to downward movement of the heel shall not be excessive.

As the heel is forced into pad 38 and the supports 40 are swung about the heel the sand 149 located in the pocket 148 of the pad shifts under 65 pressure to form a convex portion or wave 158 (Fig. 8) which extends generally heightwise of the heel and follows the curvature of the heel. As above stated, the sand provides a relatively firm backing for the work-engaging portion of 70 the pad. The unlaid portion of the cover positioned between the heel and the clamps 156 is tensioned throughout the covering operation. As above stated, the pad 38 is not secured to the respective supports and is therefore free to creep 75

under pressure with relation to the supports as the cover is applied to the heel. Although the supports 40 are illustrated as being mounted for swinging movement about fixed pivots it will be understood that in defining the supports as being mounted for angular movement it is not intended that the axes about which the supports are swung shall necessarily be fixed.

Each of the clamps 152 is pivotally mounted upon a rod 160 which is secured by a screw 162 to a clamp carrier 164 mounted upon the bearing 32. The clamps 152 are normally retained in their lowered positions upon the respective rods 160 by springs 166 the rear end of each of which is secured to the rod 160 and the front end of each of which engages an end of a notch 167 formed in the clamp. After the clutch 126 has been tripped to operate the machine the clamps 152 (Fig. 5) are swung downwardly into engagement with the respective lateral margins of the cover supported by the pad 38, under the action of a strong spring 168, the lower end of which is secured to a rear extension 170 of the carrier 164 and the upper end of which is secured to the bracket 34.

In order to insure that the clamps 152 shall not be engaged by the pad 38 wrapped about the heel or by the closed supports 40 (Fig. 4) during the indexing of the turret 48, the clamps 30 are positively moved to raised positions against the pressure of the spring 168 by a connecting rod 172. The upper end of the connecting rod 172 is pivotally secured to the rearward extension 170 of the clamp carrier 164 and the lower 35 end of the connecting rod is pivotally secured to a bell-crank lever 174 which is held against an open cam track 176 by the spring 168. After the turret 48 has been indexed the clamps 152 are permitted to move downwardly under action of the spring 168 until they are positioned just 40 above the margins of the open pad 38 (Fig. 1).

As the supports 40 and the lateral margins of the pad 38 are swung upwardly the clamps 152 swing inwardly (Fig. 9) about the respective rods 45 160 against the action of springs 166, and after turning through approximately 90° are rotated about the bearing 32 against the action of the spring 168. After the cover has been applied to the heel (Fig. 14) a high portion of the cam track 50 176 moves into engagement with the bell-crank lever 174 to raise the clamps 152 above the closed supports 40 (Fig. 4).

The heel holder 30 is operated by a rod 178, the upper end of which is pivotally secured to the 55 rear end of the lever 116 and the lower end of which is adjustably secured through the provision of a slot 180 to a bell-crank lever 182 which carries a roll 184 constructed and arranged to engage within a cam groove 186. The clamps 152 lead the holder 30 in order to insure that the margins of the cover are forced against the pad 38 before the heel 22, carried by the holder 30, forces the cover into the pad.

After the heel 22 has been covered the front 60 abutment 93 is swung away from the rear abutment 94 and the holder is raised above the closed supports 40 to permit the turret 48 to be indexed. Suitable mechanism which will be described later is provided for causing the supports 40 to retain 65 the pad 38 in clamped relation with the heel until the unit of the turret has been indexed to a discharge station 188 (Fig. 3).

The supports 40 are swung about their respective axes 154 by a pair of arms 190 provided with 70 rolls 192, respectively, which move into engage-

ment with faces 194 (Fig. 12) of the supports. The arms 190 are pivotally secured to a slide 196 (Fig. 2), a rear portion of which is mounted for vertical movement along a guideway 198 (Fig. 4) formed in the circular cover 90. The slide 196 5 carries a rearwardly extending cam roll 200 constructed and arranged to engage within a groove 202 of a cam 204 secured to the forward end of the cam shaft 58. The lower ends of the arms 190 carry rolls 206 (Figs. 2 and 4) which engage 10 within guideways 208 formed in the rear face of a cam plate 210. The cam plate 210 is provided with a pair of elongated slots 212 (Fig. 2) of suitable size to receive screws 214, respectively, which are in threaded engagement with the circular 15 cover plate 90. It will be noted that the upper ends of the guideways 208 diverge from the plane of swinging movement of the holder 30 in order to cause the arms 190 to swing toward each other at the top of their strokes. With such an arrangement the supports 40 are moved sufficiently 20 close to each other to insure that they shall effectively apply covers to the lateral margins of the attaching, the breast, and the top-lift receiving faces, respectively, of the heel as above 25 described.

In order to retain the supports 40 in their closed positions (Figs. 11 and 12) while the turret 48 is being indexed to the discharge station 188 (Fig. 3), each of the supports 40 is provided with a rearwardly extending lug 216 arranged to engage a serrated lever 218 (Fig. 5) which is pivoted upon a bracket 220 secured to the turret 48 and is rigidly connected to an arm 222. The arm 222 carries a roll 224 which is constantly urged by a 30 spring 226 (Figs. 4 and 10) against a bar 228 which is supported by a projection of the bracket 220. The bar 228 is normally in contact with the projection of the bracket 220 under action of a spring 230 surrounding a rod 232 which is secured 35 to the bar 228 and carries a roll 234. As the supports 40 are swung to their closed positions they force the lugs 216 against the respective serrated arms 218 which swing upwardly against the tension of the springs 226 (Fig. 4). The serrated 40 arms 218 thus prevent the supports 40 from opening under action of the pad 38 after the arms 190 have been lowered. In order to permit the supports 40 to open when the unit has been indexed to the discharge station 188 (Fig. 3) a cam 45 236 is secured to the frame of the machine. As each of the rolls 234 (Fig. 4) engages the cam 236 the rod 232 raises the bar 228 against the action of the spring 230 and forces the arms 222 which are already held in raised positions upwardly, thereby swinging the serrated levers 218 50 upwardly out of engagement with the lugs 216 and permitting the supports 40 to drop to their open positions. The covered heel is then removed 55 from the machine.

Although the machine has been described with reference to the pad 38 having the pocket 148 which is filled with sand, it will be understood that a pad 240 (Fig. 13) formed of a single piece of rubber may be used. If desirable, the pad 240 60 may be provided with a pair of upstanding gages 142 which are engaged by the cover and assist the operator in positioning the same upon the pad.

Preparatory to covering the heel, the edge portions of which have been coated with cement, 65 the operator forces the attaching face of the heel against the gripper plate 122 and simultaneously therewith moves the lip of the heel into engagement with the gage 123 and also moves the breast and tread faces of the heel into 70 75 engagement with the gage 123.

gagement with the abutment 98. After placing the cover upon the pad 38 the operator steps upon the treadle 125 thereby tripping a one-revolution clutch 126. As the cam 142 rotates 5 the rod 130 is lowered to permit the abutment 98 to force the heel under action of the spring 114, against the teeth 96 of the abutment 94, the clamps 152 in the meantime being lowered under the action of the spring 168 to force the margin 10 of the cover against the pad 38. The holder is then swung downwardly to force the heel against the cover and into the pad thereby applying the cover to the rear face of the heel progressively from the attaching end to the tread end of the 15 heel. When the cover has been applied to the rear face of the heel the arms 190 are raised and at the top of their stroke are swung toward each other to move the supports 40 to their closed positions thereby applying the cover to the sides 20 of the heel as well as to the margins of the breast, the tread, and the attaching faces of the heel. After the heel has been covered the holder 38 and the clamps 152 are raised and the arms 190 are lowered to permit the machine to be indexed. 25 The supports 40 are held in their closed positions when the arms 190 have been lowered, by the serrated levers 218, which are in engagement with the lugs 216 of the respective supports 40. When the machine has been indexed to the discharge station 188 the cam 236, through the above-described mechanism, forces the serrated levers 218 away from the lugs 216 and permits the supports 40 to be lowered under action of the pad to their open positions. The covered heel 30 is then removed from the machine.

Having described my invention, what I claim as new and desire to secure by Letters Patent of the United States is:

1. In a covering machine, means for applying a cover to the rear face of a heel progressively from one end of the heel to the other, and cooperating means for then applying said cover to opposite sides of the heel progressively toward the breast of the heel.
2. In a covering machine, a holder for a heel, a resilient pad, and means for effecting relative movement of the holder and the pad, said holder and said pad being constructed and arranged to apply a cover to the rear face of the heel progressively from one end of the heel to the other and then to apply the cover progressively to opposite sides of the heel during said relative movement.
3. In a covering machine, a holder for a heel, means comprising a resilient pad, and mechanism for effecting relative angular movement of the holder and the pad in a path disposed in parallel relation to a plane extending generally heightwise of the heel and also in a path disposed in parallel arrangement to a plane extending generally transversely of the heel to apply a cover to the heel.

4. In a covering machine, a holder for a heel, a resilient pad, and mechanism for angularly moving the holder substantially in a path disposed in parallel relation to a plane and simultaneously therewith angularly moving portions of the pad in paths disposed in parallel relation 60 respectively to planes which are disposed at substantial angles to said first-named plane.

5. In a covering machine, a holder for a heel, a deformable pad, supports for the pad, and means for effecting relative movement of the holder and the supports to cause a cover sup-

ported by the pad and the heel carried by the holder to be forced against each other, said holder and said supports being constructed and arranged to form a traveling wave in the pad during said relative movement whereby to cause 5 a convex portion of the pad progressively to apply the cover to the heel as it tensions the cover.

6. In a covering machine, a holder for a heel, a deformable pad containing material which resists displacement to a considerable extent, supports for the pad, and means for effecting relative movement of the holder and the supports to cause a cover supported by the pad and the heel carried by the holder to be forced against each other, said holder and said supports being 10 constructed and arranged to form a relatively hard convex portion of the pad which progressively applies the cover to the heel while stretching the same.

7. In a covering machine, a holder for a heel, 20 a relatively thick resilient pad having a pocket filled with sand, supports for the pad, and means for effecting relative movement of the holder and the supports to cause a cover supported by the pad and the heel carried by the holder to be 25 forced against each other, said holder and said supports being constructed and arranged to form a traveling wave in the pad during said relative movement whereby to cause a convex portion of the pad progressively to apply the cover to the 30 heel as it tensions the cover.

8. In a covering machine, a holder for a heel, a resilient pad having a pocket filled with a displaceable material, and means for effecting relative movement of the holder and the pad, the 35 holder and the pad being constructed and arranged to apply a cover supported by the pad to the rear face of the heel progressively from one end of the heel to the other and then to apply the cover progressively to opposite sides of the 40 heel.

9. In a covering machine, a holder for a heel, a deformable pad, members for supporting the pad, means for moving the holder to force the heel against a cover and into the pad thereby 45 applying a portion of the cover to a portion of the heel, means for moving said members to wrap the pad about the heel thereby applying other portions of the cover to other portions of the heel, and mechanism movable with and under pressure 50 of the pad constructed and arranged to cause the unlaid portion of the cover upon the pad to be tensioned.

10. In a covering machine, a holder for a heel, a resilient pad, means for effecting relative movement of the holder and the pad to apply a cover 55 mounted upon the pad to the heel, and a pair of clamps for forcing the cover against the respective lateral margins of the pad during the cover-applying operation, each of said clamps being 60 mounted for movement about two axes disposed at substantial angles to each other.

11. In a covering machine, a holder for a heel, a resilient pad, means for swinging the holder in a path disposed in parallel relation to a plane to 65 force the heel against a cover which is in engagement with the pad thereby to apply a portion of the cover to the heel, means for swinging the lateral margins of the pad toward said path of movement of the holder to apply other portions 70 of the cover to the heel, resilient mechanism, and a pair of holdown clamps each of which is movable about two axes disposed at right angles to one another, said clamps being constructed and arranged to force the cover against the lateral 75

- margins of the pad under action of said resilient mechanism in order to tension the cover forced into the pad by the heel during the heel-covering operation.
- 5 12. In a covering machine, a holder for a heel, means for swinging the holder in a path disposed in parallel relation to a plane, a pad for supporting a cover, spaced members for supporting the pad, means for swinging the members toward and away from said path, resilient means, and a pair of clamps for forcing the respective lateral margins of the cover against the pad, each of said clamps being mounted for movement against the action of said resilient means.
- 10 13. In a covering machine, a holder for a work piece, a resilient pad for supporting a cover, said holder being mounted for angular movement in a plane, a pair of pad supports positioned at opposite sides of and spaced from said plane, and means for operating the holder and the supports to apply the cover to the work piece.
- 15 14. In a covering machine, a holder for a work piece, said holder being mounted for movement about an axis, a resilient pad for supporting a cover to be applied to the work piece, a pair of supports for the pad, each of said supports being movable about an axis which is disposed at a substantial angle to the first-named axis, and means for moving the holder and the supports to apply said cover to the work piece.
- 20 15. In a covering machine, a holder for a heel, a resilient pad of substantial thickness for supporting a cover, a pair of members constructed and arranged to support the pad and spaced to form an opening which is bridged by the pad, means for forcing the rear face of the heel against the cover supported by the pad and into said opening to apply the cover to said rear face, and means for swinging said members around the heel to apply the cover to the sides of the heel.
- 25 16. In a covering machine, a holder for a heel, a pair of members spaced to form an opening, a pad of resilient material a central portion of which is constructed and arranged to fit within said opening and the lateral margins of which are supported by the respective members, mechanism for swinging the holder with relation to the pad to apply a cover to the rear face of the heel progressively from one end of the heel to the other, and means for swinging the respective members around the heel to apply the cover to the side faces of the heel, the lateral margins of the pad being free to move with relation to said members during the covering operation thereby permitting the pad to creep under pressure relatively to said members.
- 30 17. In a covering machine, a pair of members spaced to form an opening, a pad supported by said members and extending into said opening, a holder for a heel, and means for moving the holder to force the heel against a cover supported by the pad and into the opening, said members being mounted for swinging movement about axes which are positioned near opposing sides of the respective supports and which overlie portions of the respective pad-supporting surfaces of the supports.
- 35 18. In a covering machine, a holder for a heel, a pair of members spaced to form an opening, a pad of resilient material for supporting a cover, said pad being constructed and arranged to fit within the opening and having lateral portions which are supported by the respective members, mechanism for swinging the holder relatively to the pad to force the rear face of the heel pro-
- 40 gressively heightwise against the cover and into the pad thereby applying the cover to the rear face of the heel, and means for swinging the members about the heel to apply the cover to the sides of the heel.
- 45 19. In a covering machine, a holder for a heel, a resilient pad, a support for the pad, means for effecting relative movement of the holder and the pad in a curved path to apply a cover positioned between the heel and the pad to the rear face of the heel, said support comprising portions constructed and arranged to engage opposite sides respectively of said pad, and means for swinging said portions of the support toward the path of movement of the holder to apply the cover to the sides of the heel, the pad being free to creep with relation to the support as the cover is applied to the heel.
- 50 20. In a covering machine, a holder for a heel, a deformable pad, a support for the pad, means for operating the holder to apply a portion of a cover supported by the pad to the heel, said support comprising portions movable relatively to each other to apply other portions of the cover to the heel, and clamps for forcing the cover against the pad during the covering operation, each of said clamps being mounted for movement with and under pressure of the pad.
- 55 21. In a covering machine, a holder for a heel, a resilient pad constructed and arranged to be engaged by a cover, a pair of members for supporting the pad, said members being arranged to provide an opening one end of which is wider than the other, mechanism for operating the holder to force the heel against the cover supported by the pad and into said opening thereby to apply the cover to the rear face of the heel, and means for swinging the respective members about axes which extend generally lengthwise of the opening and are positioned in close proximity to the respective sides of the opening thereby to apply the cover to the sides of the heel.
- 60 22. In a covering machine, a holder for a heel, a deformable pad to be engaged by a cover, a pair of members for supporting the pad, said members being arranged to provide an opening one end of which is wider than the other, and mechanism for operating the holder to force the heel against the cover supported by the pad and into said opening, each of said members being mounted for movement about an axis which is spaced from the opening and overlies the pad-engaging face of such member.
- 65 23. In a covering machine, a holder for a heel, a relatively thick pad of deformable material, a pair of supports opposing sides of which are spaced to form an opening, the supports being mounted for movement about axes respectively, and means for operating the holder and the supports to apply a cover to the heel, said axes being so arranged that said opposing sides of the respective supports move away from each other as the cover is being applied to the heel.
- 70 24. In a covering machine, a holder for a work piece, a resilient pad for supporting a cover to be applied to the work piece, and a pair of rigid supports for the pad, the supports being spaced to form an opening and being mounted for movement about axes extending generally lengthwise of and arranged in close proximity to the opposing sides of the respective supports.
- 75 25. In a covering machine, a holder for a heel, a deformable pad for supporting a cover, said holder comprising abutments constructed and

arranged to engage the top-lift receiving and the attaching faces respectively of the heel, resilient means for normally urging one of said abutments toward the other to clamp the heel, mechanism 5 for moving said one abutment away from the other abutment against the action of said resilient means during a portion of the cycle of operation of the machine, and means for moving the holder with relation to the pad.

10 26. In a machine for covering heels, a turret, a plurality of units mounted upon the turret, each of said units comprising a resilient pad and supports for the pad, a holder for a heel, mechanism for operating the holder to force the heel into the 15 pad of one of the units which is arranged in the path of movement of the holder thereby to apply a cover mounted upon the pad to the rear face of the heel, means for operating the supports of said one unit to cause the pad to apply the cover 20 to the sides of the heel, means for indexing the turret, and means for retaining the pad in wrapped relation with the heel during the indexing of the turret.

27. In a covering machine, a turret, a plurality 25 of units mounted upon the turret, each of said units comprising a deformable pad and supporting means therefor, a heel holder, means for operating the heel holder with relation to the turret to apply a cover supported by the pad to the rear 30 face of a heel carried by the holder, mechanism for operating the pad-supporting means to apply the cover to the sides of the heel, and mechanism for indexing the turret.

28. In a covering machine, a turret, a plurality 35 of units mounted upon the turret, each of said units comprising a deformable pad and a pair of spaced supports therefor, a heel holder, means for swinging the holder and the supports relatively to each other to apply a cover mounted 40 upon the pad to the heel, means for retaining the pad in wrapped relation with the heel during a predetermined arc of travel of the turret, and means for releasing the supports to permit the same to swing away 45 from each other when the turret has been indexed to a predetermined position preparatory to removing the covered heel from the machine.

29. In a covering machine, a holder for a heel, a pad for supporting a cover, members for supporting the pad, means for moving the holder in a predetermined path to force the heel against the cover and into a portion of the pad, and means for swinging said members during a portion of the movement of the holder in said path.

30. In a covering machine, a holder for a heel, a pad for supporting a cover, means for moving the holder in a curved path to cause the heel to be forced against the cover and into the central portion of the pad thereby to apply the cover to the rear face of the heel, and a pair of rigid supports for swinging the margins of the pad around the heel as the holder continues to move in said path thereby to apply the cover to the sides of the heel.

31. In a covering machine, a heel holder mounted for movement about an axis, a cover-applying pad, supports for the pad, said supports being mounted for movement about axes respectively disposed at right angles to said first-named axis, and means for simultaneously swinging the holder and the supports about the respective axes.

32. In a covering machine, a pair of supports spaced to form an opening, a pad positioned upon the supports and extending into the opening, a holder for a heel, and means for operating the

holder to force the heel against a cover supported by the pad and into the opening thereby to apply the cover to the rear face of the heel, said supports being constructed and arranged to apply the cover to the sides of the heel as the heel is forced 5 into the pad by the holder and simultaneously therewith to increase the width of the opening to permit the heel to be forced readily into the opening.

33. In a covering machine, a turret having a 10 plurality of units which may be moved successively to an operating station and each of which comprises a resilient pad, means for cooperating with the respective units successively arranged at said operating station to wrap the pads around heels 15 thereby to apply covers supported by the pads to the heels, means for locking the pad in wrapped relation with the heels, means for indexing the turret, and means for permitting each of the pads to be released from its wrapped relation with the 20 heel after the unit has been indexed to a predetermined position preparatory to removing the heel from the machine.

34. In a covering machine, a holder for a heel, a resilient pad, a pair of members for supporting 25 the pad, means for operating the holder to force the heel against a cover upon the pad and into the pad thereby to apply a cover to a portion of the heel, said members being mounted for angular movement to wrap the pad around the heel 30 thereby to apply the cover to other portions of the heel, mechanism for operating said members, and means for varying the extent of angular movement of the members.

35. In a covering machine, a holder for a heel, 35 a turret having a plurality of units which may be moved successively to and past an operating station positioned adjacent to the holder, each of said units comprising a deformable pad for supporting a cover and a pair of members for supporting the pad, the holder and said members being constructed and arranged to cause the pad to apply the cover to the heel, and mechanism for indexing the turret in timed relation with the holder and the members.

36. In a covering machine, a holder for a heel, a turret having a plurality of units which may be moved successively to and past a covering station located adjacent to said holder, each of said units comprising a deformable pad for supporting a cover and a pair of members for supporting the pad, means for operating the holder and the members of a unit positioned adjacent to the holder to cause the pad to wrap the cover about and to apply the cover to the heel, means for indexing the turret, and means for maintaining the pad in wrapped relation with the heel while the turret is being indexed thereby permitting adhesive which secures the cover to the heel to dry.

37. In a covering machine, a holder for a heel, a plurality of units which may be moved successively to and past an operating station positioned adjacent to said holder, means for indexing the units, each of said units comprising a resilient pad for supporting a cover and a pair of angularly movable members for supporting the pad, mechanism for operating said holder and said members to wrap the pad about the heel thereby to apply the cover to the heel, and locking means 60 for retaining the pad in wrapped relation with the heel after the cover has been applied thereto until the heel has been indexed to a predetermined position.

38. In a covering machine, a holder for a heel, 75

- a turret comprising a plurality of units which may be moved successively to and past an operating station positioned adjacent to said holder, means for indexing the turret, each of said units comprising a deformable pad for supporting a cover and a pair of members for supporting the pad, means for swinging the holder and the members to cause the pad to apply a cover to the heel, and mechanism for varying the extent of swinging movement of the members.
- 5
39. In a covering machine, a deformable pad, a holder for a heel, a pair of supports for the pad, said holder and said supports being mounted for swinging movement to cause a cover upon the
- 10
- 15
- pad to be applied to the heel, and means for varying the extent of swinging movement of the supports.

40. In a covering machine, a deformable pad, a holder for a heel, a pair of spaced supports for the pad, means for swinging the holder, means for swinging the supports, means for temporarily preventing retractive movement of the supports, and means for varying the extent of swinging movement of the supports.

5

41. In a covering machine, a deformable pad, a holder for a heel, a pair of spaced supports for the pad, means for swinging the holder, a pair of arms for swinging the respective supports, and a ratchet device for preventing retractive movement of the supports when said arms are moved away from the supports.

LEWIS J. BAZZONI. 15
